UNITED STATES PATENT OFFICE.

CLINTON L. BELL, OF DECATUR, AND MORRIS S. KESSLER, OF AUBURN, ILLINOIS, ASSIGNEES, BY MESNE ASSIGNMENTS, TO DECATUR ROTARY DISPLAY COMPANY, OF DECATUR, ILLINOIS.

SANITARY DISPLAY AND VENDING DEVICE.

Application filed March 8, 1924. Serial No. 697,942.

This invention has reference to a sanitary display and vending device which is especially useful in grocery stores for dispensing such articles as granulated sugar, beans, rice, hominy, coffee, popcorn, feeds and like articles.

The invention has for its principal object to provide a display and vending device for grocery stores which includes a rotatable support on which are removably carried a plurality of bins or containers, each provided with a swiveled discharge spout and valve controlled outlet, adapted to be swung to a position over a counter scale for filling paper or other sacks when supplying the needs of purchasers.

A further object of the invention is to provide such bins or containers with transparent or display faces and with a gravity discharge, and also to provide a means for elevating and removing such bins or containers from their support when it is desired to replenish such bins or containers.

The invention has for a further object to provide each bin or container with an auxiliary or supplemental compartment and with a removable scoop therefor, whereby if more than the required weight of materials are released from the bin or containers the attendant may scoop up or out such excess of materials and replace the same in the container for discharge through the spouts with which said auxiliary or supplemental compartments are in communication.

The invention has for a still further object to construct such a vending device with a rotatable standard adapted to be mounted in an upstanding position near the counter of a store; said standard being provided, at a suitable elevation above the floor, with a plurality of radially arranged supporting arms on which rest or are supported bins or containers for storing and dispensing various articles of food, each bin or container being provided with a swiveled discharge spout and valve controlled outlet.

That the invention may be more fully understood, reference is had to the accompanying drawings, illustrating a preferred embodiment of the invention, in which:

Figure 1 is a side elevation, on a greatly reduced scale illustrating our improved display and vending device and its application for commercial use in a store, the dotted

lines indicating a counter and counter scale 55 and the swinging of a discharge spout thereabove, also the manner and means for removing and replacing a bin or container;

Figure 2 is a side elevation, partly in section showing one of the bins or containers 60 and in dotted lines a part of a spout;

Figure 3 is a plan view, in cross-section, as the same would appear on the line 3-3 Figure 2;

Figure 4 is an enlarged detail elevation 65 showing bins or containers and support therefor;

Figure 5 is a detail in plan, partly in section, as the same would appear on the line 5-5 Figure 4, several of the bins or containers removed;

Figure 6 is a detail in plan, partly broken away and partly in section, as the same would appear on the line 6-6 Figure 4, the bins or containers removed;

Figure 7 is an enlarged detail sectional view showing the base structure of the supports for the bins or containers and the mode of securing same to or mounting the same on the rotatable standard;

Figure 8 is an enlarged detail sectional view showing the upper end of the standard and mounting and the supporting and bracing means for the base structure to hold the bins or containers;

Figure 9 is a detail elevation, partly in section, showing the lower end of the standard and mounting, rest for the lower ends of the spouts and a part of the ratchet means, and

Figure 10 is a detail in cross-section showing the valve structure for controlling the discharge of materials through the spouts.

Like characters of reference denote corresponding parts in the drawings.

In Figure 1 for convenience, we have shown a cross-section through a store room having the floor A, the ceiling B and equipped with a counter C and counter scale D. However, these elements form no part of the invention and are merely included in the 100 description to illustrate and explain the application and use of the device.

As to the device itself, 1 designates a standard, preferably a pipe or other tubular member arranged in an upstanding position 105 between the floor A and ceiling B and behind and adjacent the counter C in proximity to the counter scale D, as shown. The

lower end of said standard rotates in or on a ball-bearing base 2, of any preferred or desired construction, secured to the floor, see Figure 9. The upper end of said standard preferably stops short of the ceiling B and has telescoped therein a non-rotatable extension 3, between which and the standard is a ball-bearing connection 4, and the upper end of said extension 3 is secured in a coupling 5 secured to the ceiling, see Figure 8.

Secured to the standard 1 at a suitable elevated position above the counter C by set screws 6', is a supporting collar 6, and secured to said collar and extending radially therefrom are a plurality of supporting arms or frames 7. Each frame is preferably of angle iron with upturned ends so as to provide seats or rests for bins or containers 8. The arms or frames 7 are preferably V shaped with the apex of the frames secured to the collar, see Figures 6 and 7, and the side arms of each frame lies alongside the side arm of an adjacent frame, see Figures 5 and 6, and secured to and between the outer 25 ends of the side arms of said frames 7 are bracing bars 9 which extend upwardly and converging inwardly have their upper ends secured to a collar 10, see Figure 8, secured to the standard 1 at or near its upper end by set screw 10'. On the standard 1 between the collar 10 and the bearing connection 4 is a strap 11, which extends radially from the standard, and connected to the outer end of said strap 11 is a bracing arm 12 which 30 extends upwardly and inwardly and is secured to the coupling 5, see Figures 1 and 8. The elements 11 and 12 not only brace the upper end of the standard but also serve as a crane structure for a lifting device of any 35 preferred construction, but here shown as a pulley 13 and a lifting cable 14.

The bins or containers 8 are preferably V or triangular in cross-section, see Figure 3, to conform to the contour of the supporting frames 7 and that they may be compactly assembled on their supports around the standard 1. Each bin or container is provided with a bail 15 and with a cover or lid 16, and when said bins or containers are in 50 assembled position on the frames 7 the bracing bars 9 extend up therebetween, as shown.

Each bin or container is provided with an inclined bottom 17 and an auxiliary or supplemental compartment 18 therebeneath made possible by the false bottom 19. Said compartments 18 open out of the front face of the bins or container, the same to be closed by a scoop 29. The bottom 17 at its lower 55 end has a discharge opening 21 and the false bottom 19 has a discharge opening 22 and leading from said opening 22 and depending from said false bottom is a coupling 23 to which is swiveled a discharge spout 24, the 60 lower end of which normally swings in to-

ward the standard 1, see Figure 1, and may be caused to rest on the ring 25 secured to the standard 1. Providing each bin or container 8 with an inclined bottom insures a gravity feed of material from the main compartment of the bin or container through the compartment 18 and out through the spout 24. Each spout, at or near its lower end is provided with a cut-off valve 26, normally held closed by a spring 27, see Figure 10, 75 and each valve is formed or provided with a projecting finger-hold 28 for the convenient use of an attendant when a spout 24 is swung out into operative position, as shown in dotted lines, in Figure 1. Should material, in excess of the amount desired, be released from or through a spout 24 the attendant may scoop up the same with a scoop 29 and replace the same in the container by emptying the same into the compartment 18, 85 as will be understood.

The front wall of each container, above the scoop 29 is provided with an opening 29', see Figure 3, and guide-ways 30 adapted to receive a transparent slide 31 for displaying to customers, as well as the store keeper and assistants the contents of the containers and approximate amounts; also in the front wall of each container may be inserted a designating card 32 with the name of the 95 contents of the compartment thereon.

As constructed, the bins or containers are rotatably mounted so that they may be brought into registering position to discharge contents from the respective containers into a paper sack or bag resting on the scale D, when the spout 24 may be swung out and over the bag to discharge contents of the container therein. When the spout is in discharging position, as shown in dotted lines in Figure 1 it may rest on or be held in position by the rest 33 on the counter C. To hold the standard 1 and containers in registering position with the scale D, we provide a locking or retarding means, 100 preferably in the form of a notched ring 34 with which engages a spring detent or finger 35, see Figure 1. This ratchet means acts automatically and yet will permit rotation of the standard and containers in either direction.

The present arrangement for supporting the bins or containers 8 on the frames 7 provides for their removal, by lifting off so that they may be lowered to the floor, as shown in dotted lines in Figure 1, for cleaning or filling, as the case may be, and to be raised into position again on said frames. We prefer some suitable lifting means and have preferred to show the lifting cable 14 with a hook to engage the bails 15. The position of the pulley 13 is such that when a container 8 is lifted off of its support a slight outward movement of the container 115 will permit it to be lowered and to slide 120

down between the side rails 7 of a frame and to be again as easily lifted into position to rest on a frame.

Such a vender as we have shown and described may occupy a space not otherwise taken and the containers are elevated at such a height as will permit a person to walk therebeneath. Furthermore, the cost of such a device is comparatively small and the arrangement or construction of the containers and mode of discharge always guarantees to a customer fresh goods and prevents mildewing or moulding.

As shown, the parts are interchangeable and as assembled presents an attractive piece of equipment to a store.

What we claim is:—

1. A sanitary display and vending device, comprising a standard, top and bottom bearings for the standard in which the same may

be rotated, a plurality of bins connected in radial arrangement around the standard, a gravity discharge spout swingably connected with each bin, a valve for each spout to control the discharge therethrough, a rest on the standard for the free ends of the spouts, and means to hold the standard in adjusted positions. 25

2. A display bin for a vending device, having a gravity outlet, an auxiliary compartment in said bin in communication with its outlet and opening out of one face of the bin, a scoop for said auxiliary compartment constituting a closure for the latter, and a removable lid for said bin. 30

In witness whereof, we have hereunto affixed our hands this 1st day of March, 1924. 35

CLINTON L. BELL.
MORRIS S. KESSLER.
